UNITED STATES PATENT OFFICE.

WILLIAM ORD, OF CHICAGO, ILLINOIS.

SCREED FOR CONCRETE-PAVING MACHINES.

Application filed January 14, 1926. Serial No. 81,195.

This invention relates to what is known as a screed, surfacing member or strike-off member of a machine or device for compacting and surfacing concrete pavements and has for its object to provide a composite device including a flexible steel middle portion, a pair of removable and renewable inflexible end portions and removable and renewable wearing plates for said end members which are cheap and are subjected to the greatest wear, said end members, furthermore, including means for preventing excess concrete disposed in their paths from passing over the side-forms or side rails of the conventional pavement form on which said wearing plates of said end-members ride during lateral reciprocation of the screed.

The invention is applicable to machines of the type shown in Letters Patent of the United States, granted to R. D. Baker, Nos. 1,390,479 and 1,388,690, the machine of Letters Patent No. 1,522,138 to William Ord and to all other machines wherein a laterally reciprocable screed or strike-off is employed and is also applicable to manually manipulable devices of this character.

In the accompanying drawings, I have illustrated the invention as applied to the particular type and construction of screed or surfacing member embodied in the aforesaid Ord machine without limitation, however, to its application to other types and constructions.

In said drawings:

Fig. 1 is a front elevation of a screed or surfacing member constructed in accordance with the invention.

Fig. 2 is a plan view of the same.

Fig. 3 is a vertical section showing two spaced screeds, such as are illustrated in the aforesaid Ord machine.

Fig. 4 is a top plan view of an end-member of the screed or surfacing member detached from the middle portion.

Fig. 5 is an end elevation of the same.

In the instance illustrated, the surfacing member, screed or strike-off, consists of a rigid or substantially inflexible member 1,

such as a conventional steel I-beam, the web of which is vertically disposed, a conventional steel channel-bar 2, the web of which is disposed parallel with the flanges of the I-beam and whose edge-flanges extend upwardly from said web.

The said channel-bar 2 is of less length than the distance between the side-forms or said rails of the pavement form over which the screed or beam is to be laterally reciprocated and is, in fact, sufficiently short to prevent its ends from coming into contact with said side-forms, to obviate thereby the subjection thereof to the grinding due to the presence of sand and cement on the tops of the side forms.

The end-portions of the lower member of the screed consist of castings each comprising a large outer end portion 3 and a smaller inner end portion 4, the latter including a bottom plate and side flanges 5 relatively disposed and shaped to fit within the channel-bar 2 with said bottom plate resting upon the web and the side flanges 5 having their outer faces opposed to and contacting with the inner faces of the flanges of the channel-bar 2, to which they are suitably detachably secured by means, preferably, of the bolts 6. The bottom plates (indicated by reference character 4) of said inner ends of said members or castings are not co-extensive with the flanges 5, but are cut away between the extreme end portions of said flanges so as to provide a free space between said end-portions of said flanges. The latter are provided with opposed inwardly extending bifurcated projections 7 overhanging said free space and adapted to receive and engage the shanks of bolts 8 and the nuts 9 and 10 associated with the lower ends thereof.

The outer end-portions of said castings 90 comprise each, a peripheral upstanding frame element or flange 11 consisting of continuations of the flanges 5 and offset therefrom to provide shoulders 12 to abut against the ends of the flanges of the channel-bar 2. The frame elements 11 are integral with the

bottom or base flange, indicated by reference character 3, which is flush with the plate or portion 4.

The said flange 11 is provided with perforations 13 for bolts 14 by means of which wearing plates 15 are secured to the lower faces of said flanges, said plates 15 being of substantially the exact thickness of the web of the channel-bar and having peripheral edges corresponding to and flush with the outer vertical faces of the peripheral flanges or frame elements 11. As the portions of these plates 15 which ride on the side-forms are of considerably greater width than the lower face of the channel-bar, they wear away more slowly than if narrower and, being renewable at small cost and little labor, and without disturbing the adjustment of the channel-bar as to curvature, they present great economic advantage. This will be more readily appreciated when it is considered that said plates 15 must be renewed after the device or machine has completed the compacting and surfacing of approximately five miles of pavement.

The said outer end-portions of said castings have straight rear walls and straight end-walls, the latter being perpendicular to the rear walls. The front walls, however, extend angularly to the rear and end walls to provide surfaces diverging forwardly from the plane of the front face of the channel-bar. During reciprocation of the latter these angular surfaces tend to and do push masses of concrete disposed in their paths forwardly and inwardly from the side forms, thereby preventing spill over the latter with consequent waste.

Integral with the rear walls of the outer end-portions of the castings are inverted box-like formations 16 constituting bearing surfaces for guide rollers of the machine of the aforesaid Ord patent.

The said bolts 8 connect at their upper ends with yokes 17 slidably mounted on the upper flanges of the I-beams 1 and of which a number are disposed between the two shown for connection with the middle portions of the channel-bar 2 for flexing and adjusting the latter to curvature corresponding to the crown to be imparted to the pavement. The said yokes 8 and their connection with the said channel 2 are fully illustrated and described in the aforesaid Ord patent.

It will be appreciated by those skilled in the art that the average width of concrete highways is about twenty feet. The outer end portions 3 of the end members are approximately sixteen inches long and may, therefore, be inflexible.

Should the wearing plates 15 be a bit thin so as to be not quite flush with the bottom of the channel-bar when said plates 15 are secured in place, they may be properly ad-

justed to be flush by inserting washers or sheet metal or the like between their top faces and the bottom surfaces of the end members. As the bottom of the channel-bar 2 also gradually wears, the thickness of the end plates 15 must be gradually lessened as they are renewed, in order to avoid an offset between their bottom surfaces and that of the channel-bar 2.

I claim as my invention:

1. A surfacing member for the purpose specified comprising a middle member and two end members rigidly secured to each other, the end members having bottom surfaces offset upwardly from the bottom surface of the middle member and being of greater width than the middle member, and wearing plates detachably secured to the bottom surfaces of said end members and having their bottom surfaces flush with the bottom surface of the middle member and being of dimensions corresponding with those of the bottoms of the end members.

2. A surfacing member for the purpose set forth comprising a middle member having a flat bottom wall and parallel upstanding side flanges, end members each having an end portion fitting upon the top surface of the bottom wall of said middle member and between the flanges of the latter and the including extension portions having each a bottom wall and a peripheral upstanding flange, the latter presenting a shoulder against which a flange of the middle member abuts, the bottom surfaces of the bottom walls of said extension portions being offset upwardly from the bottom surface of the middle member a distance substantially equal to the thickness of wearing plates, and wearing plates of substantially said thickness detachably secured to the bottom surfaces of said end members.

3. A surfacing member for the purpose specified, including a flexible middle member having parallel front and rear faces, inflexible end members secured to the respective ends of said middle member and having rear faces disposed parallel with the rear face of said middle member, the front portions of said end members presenting vertical faces extending at an incline to and projecting forwardly of the front face of the middle member, the inclined front faces of said end members converging toward the front face of the middle member, wearing plates detachable secured to the bottoms of said end members with their lower faces substantially flush with the lower face of the middle member and abutting at their ends against the ends of said middle member, the said wearing plates being of greater width than the middle member over the portions thereof mainly subjected to wear.

4. A surfacing member for the purpose specified including a middle flexible member

having a flat bottom wall adapted to be flexed to a desired curvature, and end members each having an inner end portion overlapping and rigidly secured to said middle member, the outer end portions of said members including a flat bottom wall and wearing plates abutting the ends of said middle member and having their bottom faces dis- posed substantially flush with the bottom surface of said middle member, said outer end portions of said end members presenting front walls angularly disposed to and projecting forwardly of the front of said middle member.

WILLIAM ORD.
